UNITED STATES PATENT OFFICE

2,608,400

PERCUSSION COAL BREAKING MECHANISM

Eldon C. Allen, Harrisburg, Ill.

Application July 21, 1950, Serial No. 175,157

6 Claims. (Cl. 262—9)

1

My invention relates to improvements in percussion coal-breaking mechanism, for coal undercutting mining machines especially, although not necessarily.

The primary object of my invention is to provide in a coal mining machine of the type including a forwardly travelling and swingable cutter bar, percussion mechanism for impacting the coal with sharp powerful blows to break down and disrupt the coal at opposite sides of the cutter bar.

Another object is to provide percussion mechanism for the purpose set forth which is automatically operated by comparatively low fluid pressure to impact the coal with sufficient force to break the coal down.

Another object is to provide in such mechanism for automatic operation thereof under control of swinging movement of the cutter bar.

Still another object is to provide percussion mechanism for the above purposes which will not interfere with forward travel, nor swinging, of the cutter bar.

Still another object is to provide such mechanism which is simple in construction, comparatively inexpensive to install, service and manufacture, and is substantially fool-proof.

Other and subordinate objects within the purview of my invention, together with the precise nature of my improvements, will be readily understood when the succeeding description and claims are read with reference to the drawings accompanying and forming part of this specification.

In said drawings:

Figure 1 is a fragmentary view in side elevation, partly broken away and shown in section, of my improved percussion mechanism embodied in a coal mining machine of the type specified;

Figure 2 is a fragmentary view in side elevation, drawn to a larger scale, of the front end of the cutter bar and one of the pistons, or rams;

Figure 3 is a view in longitudinal section taken on the line 3—3 of Figure 2;

Figure 4 is a fragmentary view in longitudinal section, drawn to a larger scale and broken away, of the pressure discharge means for projecting the pistons outwardly;

Figure 5 is a view in transverse section taken on the line 5—5 of Figure 4 and drawn to a larger scale;

Figure 6 is a similar view taken on the line 6—6 of Figure 4;

Figure 7 is a fragmentary view partly in side elevation and partly in section illustrating the

2

operation of the operating means for the master fluid control valve; and

Figure 8 is a view similar to Figure 4 illustrating the parts of the pressure discharge means positioned for discharge of pressure by said means.

Referring to the drawing by numerals, my improved percussion coal breaking mechanism has been shown therein embodied in a usual type of mining machine, shown fragmentarily and conventionally, as sufficient for the present purpose, and which embodies a mechanism housing 1 on a skid base 2 for movement along the floor 3 of a mine in a manner which will be understood in the art to feed a front, forwardly extending cutter bar 4 into a vein of coal. The cutter bar 4 includes a pair of laterally spaced side frames 5 suitably secured together, in a manner not shown, and is pivotally mounted at its rear end, by a transverse rock shaft 6, in the upper front portion of the housing 1 to incline downwardly and forwardly out of a slot 7 in said housing for vertical swinging of said bar on said shaft 6. The cutter bar 4 carries the usual, well understood, endless cutter chain 8 running around the front end of said bar with cutter teeth 9 thereon and which is driven by means, not shown, counter-clockwise as viewed in Figure 1, to undercut a vertical slot 10 in the coal 11. During undercutting, by 15 the cutter chain 8, the cutter bar 4 swings upwardly and downwardly intermittently due to tendency of the front end of said bar to climb upwardly in the coal and because of operation of the cutter teeth 9 against the coal, all as will be understood in the art.

According to my invention, a pair of opposed pistons, or rams, 12, 13 are mounted in the front end of the cutter bar at opposite sides thereof to slide outwardly and inwardly of said bar laterally thereof in a hollow cylinder 14 extending transversely through said frames 5 and suitably fixed by welding 15 in openings 16 in said frames 5. The pistons 12, 13 are axially aligned and normally spaced apart. An annular, internal central shoulder 17 in the cylinder 14 limits inward sliding of the pistons 12, 13.

Spring tension means connects said pistons 12, 13 to slide the same inwardly into the inward limit of movement thereof, in which said pistons 12, 13 seat against opposite sides of the shoulder 17 in spaced apart relation and project slightly outwardly of opposite sides of the cutter bar 4. The spring tension means comprises an axial bolt 18 threaded in the piston 13 and extending 55 into an axial bore 19 in the piston 12, and a

coil spring 20 surrounding said bolt 18 in said bore 19 between the head 18' of said bolt and the outer end of an axial hollow stem 12' on the inner end of the piston 12 provided for extending the bore 19 to accommodate a spring of sufficient length when expanded to hold said pistons 12, 13 retracted against the shoulder 17. A threaded plug 19' in the outer end of the piston 12 closes the outer end of the bore 19. An axial well 23 in the inner end of the piston 13 accommodates the stem 22 to permit said pistons 12, 13 to seat against the shoulder 17 in close-together, spaced apart relation.

Stop means for limiting outward sliding or projection of the pistons 12, 13 is provided, as follows: Circumferentially spaced bolts 24 in said pistons 12, 13 slidably extend through the inner confronting ends of said pistons into circumferentially spaced recesses 25 in both said pistons. End nuts 26 on the bolts 24 working in said recesses 25 and adapted to engage the bottoms of said recesses coact with said bottoms to limit outward sliding of said pistons 12, 13. Screw plugs 27 in the outer ends of the pistons 12, 13 close the outer ends of the recesses 25.

The pistons 12, 13 are slid, or projected, outwardly under the action of pressure discharge means now to be described.

A longitudinally extending hollow cylinder 30 in the cutter bar 4, between the frames 5, is threaded at its front end into a radial pressure discharge neck 31 on the cylinder 14, said neck opening into the space between the pistons 12, 13. The front end of said cylinder 30 is threaded against an annular valve seat 32 in said neck 31 for seating a pressure discharge control valve, presently described in detail. A cylindrical cap section 33 is threaded onto the rear end of said cylinder 30 with a follower piston 34 working therein.

The follower piston 34 is backed by a coil spring 35 in the cap section 33 and normally seated thereby against a shoulder 36 formed by the rear end of said cylinder 30. A valve stem 37 is carried in the cylinder 30 and cap section 33 by the follower piston 34 and is endwise slidable in an axial bore 38 in said follower piston 34 with a conical pressure discharge control valve 39 on the front end of said stem for seating in the before-mentioned valve seat 32 to close the discharge neck 31.

A coil spring 40 on the valve stem 37 bearing against the front face of the follower piston 34 and against a collar 41, secured on said stem by a pin 42, urges said stem forwardly in the follower piston 34 to seat said valve 35 when said follower piston 34 is in its described normal position, said spring 40 tensioning the valve stem 37 against rearward movement in said follower piston 34.

A coil spring 43 on the valve stem 37, between the rear face of the follower piston 34 and a nut 44 on the rear end of said stem 37, yieldingly opposes rearward movement of the follower piston 34 from normal position relative to said stem 37 and for a purpose presently seen. A bracket 45 mounts the cylinder 30 to said cutter bar 40.

As will presently more clearly appear, the cylinder 30 and the cap section 33 provide fluid pressure chambers 46, 47, respectively, in front of and in the rear of the follower piston 34.

A spring loaded, forwardly opening by-pass valve 48 in the follower piston 34, normally closes a by-pass port 49 in the follower piston 34 and opens said port 49 under fluid pressure in the

pressure chamber 46 to by-pass pressure from chamber 47 to chamber 46.

A nipple 50 in the rear end of the cap section 33 provides for admitting fluid under pressure into the pressure chamber 47 in the rear of the follower piston 34 and for discharging fluid under pressure from said chamber 47 all for a purpose presently apparent. An air inlet nipple 52 on the rear end portion of the cylinder 30 provides for feeding fluid under pressure into the pressure chamber 46 forwardly of the follower piston 34 for a purpose which will also presently appear.

A master fluid control valve 55 is suitably secured by bolts 56 in the housing 1 with a rotary valve core 57 having a diametrical port 58, a radial branch port 59 extending from said port 58, and a peripheral exhaust port 60 adapted to discharge outside said valve. A fluid pressure supply line 61 with a suitable cut-off valve 62 therein extends from a source of fluid under pressure, not shown, to said valve 55. A fluid pressure feed and discharge line 64, in part flexible, extends from said valve 55 to the beforementioned nipple 50. A fluid pressure feed line 65, also in part flexible, extends from said valve 55 to the inlet nipple 52 for the pressure chamber 46.

The valve core 57 is rotatable for control purposes upon upward and downward swinging of the cutter bar 4 by valve operating mechanism described in the following. A crank arm 70 depends from one end of the rock shaft 6 and is loose on said shaft. A hand lever 71 formed on said crank arm 70 with the usual detent dog 72 thereon for engagement with a toothed sector 73 fast on the shaft 6 provides for locking said crank arm 70 to said shaft 6 for swinging by vertical swinging of the cutter bar 4, said hand lever providing for variable adjustment of said crank arm 70 angularly on said shaft 6 for a purpose to be explained.

The crank arm 70 is connected by a pin 74 and slot 75 to one end of a toothed rack bar 76 horizontally slidable endwise in guides 77 suitably bolted in the housing 1, as at 78. The rack bar 76 meshes with a gear pinion 79, keyed, as at 80, to a shaft 81 journaled in the housing 1 and having suitably fixed thereon a cam toothed wheel 82. As will be seen, by swinging of the crank arm 70 in opposite directions, endwise sliding movement is imparted to the rack bar 76 to rotate the cam toothed wheel 82.

A roller 83 on one end of a bellcrank 84, pivoted as at 85 in the housing 1, rides the cam toothed wheel 82, said bellcrank 84 being tensioned by a suitably connected coil spring 86 to hold said roller against said wheel 82 whereby said bellcrank 84 is rocked from a normal position by the teeth of the toothed wheel 83 and returned to normal position by said spring 86. A link 87 is pivoted at one end, as at 88, to the other end of the bellcrank 84 with its other end pivoted, as at 89, to a crank arm 90 fixed on an axial stud 91 on the valve core 57, and whereby rocking of the bellcrank 84 out of and into normal position rotates said core 57 out of and back into normal position.

Referring now to the operation of my improved mechanism, with the roller 83 riding the cam toothed wheel 82, between the teeth of said wheel, the bellcrank 84 is held by the coil spring 86 in its normal position, shown in Figure 1, and thereby holds the valve core 57 in its normal position, 75 also shown in Figure 1. In the normal position

of the core 57, the ports 58, 59 communicate the fluid pressure supply line 61 with the fluid pressure feed and discharge line 64 so that, valve 62 being open, fluid under pressure is fed into the pressure chamber 47 slowly through a restricted port 51 in nipple 58. When the fluid pressure in the chamber 47 builds up to line pressure, it opens the by-pass valve 48 to admit fluid from chamber 47 into chamber 46 until the pressure in said chambers 47, 46 is equalized, the fluid pressure chamber 46 then coacting with coil spring 44 in holding the pressure discharge control valve 39 seated.

When the cutter bar 4 swings, up or down, sufficiently to cause endwise movement of the rack bar 76 and consequent rotation of the cam toothed wheel 87 to the extent that the roller 83 rides onto a tooth of said wheel, the bellcrank 84 is swung from normal position in opposition to the coil spring 86 to cause rotation of the valve core 57 from its normal position, clockwise as viewed in Figure 1, until the branch port 59 and the diametrical port 58 communicate the fluid pressure supply line 61 with the fluid pressure feed line 65 and also communicate the exhaust port 60 with the fluid pressure feed and discharge line 64, all as shown in Figure 7.

When the valve core 57 is rotated from normal position, as described in the foregoing, fluid under pressure is discharged from chamber 47 slowly through port 51 and line pressure is admitted to the chamber 46 so that the piston follower 34 is moved rearwardly under the fluid pressure in the chamber 46 and along the valve stem 37 in opposition to the coil springs 35 and 43, thus disabling coil spring 40, all while the fluid pressure discharge valve 39 is held to its seat by pressure in said chamber 46. When the follower piston 34 has moved back sufficiently to overcome the fluid pressure against the fluid pressure discharge control valve 39, said valve is suddenly opened, as shown in Figure 8, and coil spring 43 then expands to slide the valve stem 37 rearwardly in the follower piston 34 until coil spring 40 and coil spring 43 balance said stem in said follower piston.

As the fluid pressure discharge valve 39 is opened, a burst of fluid under pressure is discharged from chamber 46 into the space between the pistons 12, 13 to slidably project said pistons outwardly and impact the same against the coal 11 at opposite sides of the cutter bar 4 to break and disrupt the coal. The fluid pressure then discharges slowly around said pistons 12, 13 to atmosphere and the coil spring 20 returns the pistons 12, 13 into their limit of movement inwardly of the cylinder 14. Back pressure release ports 92 are provided in the bottoms of the recesses 25 for a purpose which will be apparent. As the fluid pressure discharges from the chamber 46, the coil spring 35 returns the follower piston 34 against the shoulder 36, said piston 34 moving the valve stem 37 forwardly to seat the fluid pressure discharge control valve 39 and compress the coil spring 40 so as to tension said valve against the seat 32 for closing the neck 31.

As soon as the roller 83 rides off a tooth of the toothed wheel 82, the bellcrank 84 and valve core 37 are returned to normal position by the fed to chamber 47 to be by-passed through by-coil spring 86 and fluid under pressure is again pass port 49 into the chamber 46 in the manner already described, thereby completing a cycle of operation of the percussion mechanism. The percussion mechanism completes a cycle of oper-

ation each time the roller 83 rides onto and off a tooth of the toothed wheel 82 and upon swinging of the cutter bar 4 either upwardly or downwardly sufficiently to cause said roller to ride onto and off of a tooth of said toothed wheel. By adjusting the crank arm 70 into different set positions, through the hand lever 11, detent 12 and sector 13, the toothed wheel 82 may be preset to time operation of the master fluid control valve 55 relative to swinging of the cutter bar 4 as desired.

The foregoing will, it is believed, suffice to impart a clear understanding of my invention without further explanation.

15. Manifestly, the invention as described is susceptible of modification, without departing from the inventive concept, and right as herein reserved to such modifications as fall within the scope of the appended claims.

Having described the invention, what is claimed as new is:

1. In a coal mining machine, the combination with a pivotal coal cutter bar swingable on its pivot, of percussion mechanism for breaking coal at opposite sides of said bar comprising a pair of axially aligned spaced apart pistons slidably mounted on said bar for projection outwardly of said bar at opposite sides of the same to impact the coal, means to intermittently introduce fluid under pressure into the space between said pistons to project said pistons intermittently including a fluid controlled valve, and means to operate said valve by swinging movement of said bar settable to variably time operation of said valve relative to swinging of said bar.

2. In a coal mining machine, the combination with a pivoted coal cutter bar swingable on its pivot, of percussion mechanism for breaking coal at opposite sides of said bar comprising a pair of coaxial spaced apart pistons slidably mounted on said bar for projection outwardly of said bar at opposite sides thereof to impact the coal, and means to intermittently introduce fluid under pressure into said space to project said pistons intermittently controlled by swinging movement of said bar comprising a fluid pressure discharge cylinder carried by said bar, valve means in said cylinder for controlling the discharge of fluid opened by a predetermined fluid pressure in said cylinder, means to feed fluid under pressure into said cylinder including a normally closed fluid feed control valve, and operating connections between said bar and the fluid feed control valve for opening said valve by swinging of said bar.

3. The combination of claim 2 wherein said operating connections comprise a pivoted roller carrying lever operatively connected to said valve, a cam toothed wheel engaged by said roller for swinging said lever on its pivot, and wheel 60 rotating devices operated by said bar upon swinging of said bar.

4. The combination of claim 2 wherein said operating connections comprise a pivoted roller carrying lever operatively connected to said valve, a cam toothed wheel engaged by said roller for swinging said lever on its pivot, and rack and pinion devices for rotating said wheel operated by said bar upon swinging of said bar.

5. In a coal mining machine, the combination of a pivoted coal cutter bar swingable on its pivot, of percussion mechanism for breaking coal at opposite sides of said bar comprising a pair of coaxial spaced apart pistons slidably mounted on said bar for projection outwardly of said bar at opposite sides thereof to impact the coal, and

means to intermittently introduce fluid under pressure into said space to project said pistons intermittently comprising a fluid pressure discharge cylinder carried by said bar, a fluid pressure discharge control valve in said cylinder, a 5
slidable follower in said cylinder in which said valve is slidable into closed position, spring means between said valve and follower normally closing said valve and disabled by initial sliding of said follower, means operatively connecting 10
said follower to said valve to open the valve upon sliding of said follower after disabling of said spring means by initial sliding of the follower, and means to feed fluid under pressure into said cylinder to slide said follower controlled by 15
swinging of said bar.

6. In a coal mining machine in accordance with claim 5, said last named means comprising a fluid feed control valve, and operating connections between said bar and feed control valve.

ELDON C. ALLEN.
